[57] CLAIM

The ornamental design for a storage and transportation trunk, as shown and described.

DESCRIPTION

FIG. 1 is a front perspective view of a storage and transportation trunk showing my new design;

FIG. 2 is a bottom and left side perspective view of the storage and transportation trunk;

FIG. 3 is a top view of the storage and transportation trunk;

FIG. 4 is a front view of the storage and transportation trunk, the rear view being substantially a mirror image of the front side shown;

FIG. 5 is a right side view of the storage and transportation trunk, the left side being substantially a mirror image of the right side shown;

FIG. 6 is the bottom view of the storage and transportation trunk; and,

FIG. 7 is a second embodiment of a storage and transportation trunk showing my new design, the top, front, sides, and bottom are substantially the same as the embodiment of FIG. 1 the difference being the bottom support structures.

FIG. 1

FIG. 2

FIG. 3**FIG. 4**

FIG. 5

FIG. 6

FIG. 7
